US0D1096901S

(12) **United States Design Patent** (10) **Patent No.:** **US D1,096,901 S**
(45) **Date of Patent:** **** Oct. 7, 2025**

(54) **BIRDWATCHER CAMERA**

(71) Applicant: **Shenzhen JUNSHUO Technology Co., Ltd.**, Guangdong (CN)

(72) Inventor: **Peng Hu**, Guangdong (CN)

(**) Term: **15 Years**

(21) Appl. No.: **29/956,771**

(22) Filed: **Aug. 9, 2024**

(51) **LOC (15) Cl.** **16-01**

(52) **U.S. Cl.**

USPC **D16/208**; D30/124

(58) **Field of Classification Search**

(57) **CLAIM**

The ornamental design for a birdwatcher camera as shown and described.

DESCRIPTION

FIG. 1 is a front, right and perspective view of a birdwatcher camera, showing my new design.

FIG. 2 is a rear, left and bottom perspective view thereof.

FIG. 3 is a front and right perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof; and,

FIG. 9 is a bottom plan view thereof.

The dashed broken lines depict portions of the birdwatcher camera that form no part of the claimed design.

1 Claim, 9 Drawing Sheets
